Primary Examiner — W. A. Teddy Falloway

(74) Attorney, Agent, or Firm — JCIP GLOBAL INC.

(57) **CLAIM**

The ornamental design for a mirror as shown and described.

DESCRIPTION

FIG. 1 is a front perspective view of a mirror showing my new design;
 FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and

FIG. 8 is another front view thereof, showing an open position.
 The broken lines in the drawings represent portions of the mirror and form no part of the claim. The oblique lines shading shown in FIG. 8 represent mirror surfaces.**1 Claim, 7 Drawing Sheets**(56)
